DESIGN FOR A VIEWER

Albert A. Bechtell, St. Louis, Mo.

Application June 27, 1945, Serial No. 120,365

Term of patent 14 years

(Cl. D57—1)

To all whom it may concern:

Be it known that I, Albert A. Bechtell, a citizen of the United States, residing in the city of St. Louis, in the State of Missouri, have invented a new, original, and ornamental Design for Viewers, of which the following is a specification, reference being had to the accompanying drawing, forming part thereof.

Fig. 1 is a top plan view of a viewer showing my new design.

Fig. 2 is a side elevation thereof.

Fig. 3 is an end elevation thereof.

Fig. 4 is a bottom plan view.

I claim:

The ornamental design for a viewer, as shown.

ALBERT A. BECHTELL.
